UNITED STATES PATENT OFFICE.

MILTON L. DODGE, OF NEWBURYPORT, MASSACHUSETTS.

MACHINE FOR ATTACHING MOLDED COUNTERS TO TURN SHOES.

Original application filed March 7, 1922, Serial No. 541,667. Divided and this application filed September 27, 1922. Serial No. 590,836.

To all whom it may concern:

Be it known that I, MILTON L. DODGE, a citizen of the United States, residing at Newburyport, in the county of Essex and State of Massachusetts, have invented new and useful Improvements in Machines for Attaching Molded Counters to Turn Shoes, of which the following is a specification.

This invention relates to machines particularly intended for attaching counter stiffeners and shank pieces in position in the manufacture of turn shoes, and by which this operation may be rapidly and accurately effected, this application being a division of application Serial Number 541,667 filed March 7, 1922, method for attaching molded counters to turn shoes, in which the method herein disclosed is claimed. Heretofore these parts have usually been attached while the last is in the unturned shoe, the shoe being supported in a nailing machine by a jack having in its top a pin for engagement in a hole in the neck of the last. This jack is movable forwardly for the placing and removal of shoes and is then moved backwardly and raised up into cooperative relation to the nailing mechanism at each operation.

As is well known to those skilled in the art the position of the last pin hole varies greatly with different lasts and the lasts also vary considerably in height. In order to take care of the variations in the position of the last pin holes laterally of the last, it has been proposed to mount the last pin in a block free to slide laterally of the jack so that the operator may move it laterally as it approaches the nailing mechanism to correctly position it. The proper lateral positioning of this block, as well as vertical adjustments for varying heights of last requires considerable skill and care on the part of the operator and slows production very considerably.

According to the present invention the last is removed before the counter is attached, and a block, fitting easily within the heel portion of the shoe, is fixed rigidly to the top of the jack. The engagement of the upper at the heel end of the shoe about this block thus properly centers the shoe so that it is always presented in proper position laterally to the nailing mechanism, no adjustment being required for different shoes.

To further insure correct lateral position-

ing of the shoe relative to the nailing mechanisms, a centering guide may be employed against which the shoe is moved beneath the nailing mechanism.

By this invention, therefore, the nailing of the counter in correct position is reduced to a mechanical operation in which the exercise of special skill or judgment is unnecessary, so that the operation is very materially speeded, the production of imperfect or inferior work eliminated, and a poorer quality of labor may be employed satisfactorily, thus materially cheapening the operation.

For a more complete understanding of this invention, reference may be had to the accompanying drawings in which—

Figure 1 is a fragmentary side elevation of the machine showing the relation of the shoe supporting jack to the nailing mechanism.

Figure 2 is a detail plan of the sole and counter gage.

Figure 3 is a side elevation of the shoe supporting block used when wood heels are to be employed, other parts being shown in dotted lines.

Figure 4 is a top plan of a block used where wood heels are to be employed.

Referring first to Figure 1, at 1 is indicated a jack post which is slidable forwardly and rearwardly in suitable guides on the vertical movable slide 2. This machine may be of any suitable type of nailing machine, as herein shown it being of the well known "lightning" type. The jack 1 has at its outer end an upwardly extending post 3 which, in the ordinary use of the machine for nailing heels, is used to support the toe of the shoe. At 4 is shown an adjustable heel post to the top of which is fixed a block 5. This block in the present invention is rigidly fixed to the top of the post 4, centering pins 6 and 7 being shown to insure its correct positioning and a set screw 8 being employed to fasten the block rigidly in position.

At 10 is shown a nailing block which is designed to receive nails in suitable perforations therein and to receive driving members for driving the nails into a shoe supported on the jack 1. This block 10 is preferably provided on its lateral sides with downwardly extending fingers 11 and on its rear face with a finger 12. These fingers may be of springy material, if desired, so that a molded counter, indicated by

dotted lines at 13, may be pushed upwardly over the block 10, the fingers 11 and 12 passing outwardly thereof to retain it in position. Where shank stiffeners are to be attached also, these are assembled with the counters before the latter are positioned for attachment to the shoes. This nailing block, together with fingers, is fixed in position on the machine in a well known manner. The 10 jack 1 may be moved outwardly, away from beneath the block 10, into the position shown in dotted lines, to facilitate the placing of the shoe thereon, this being done when the slide 2 is depressed below cooperative relation with the nailing block. When the jack is in this position, an unturned shoe, the last having been removed, is placed over the block 5, the heel portion of the upper extending down around the same, as indicated in dotted lines at 14. The toe rest 3 may support the toe portion of the shoe at this time but when the nailing of the counter is being effected it performs no function in the present invention. The block 5 serves to center the shoe laterally, the upper 14 engaging about the sides thereof, so that the shoe sole is correctly related to the path of movement of the jack so that it will be brought into proper cooperative relation with the block 10, and the counter thereon, without particular care on the part of the operator.

The jack is moved rearwardly beneath the nailing block and the sole of the shoe engages between outwardly curved spaced arms 20 (see Figures 1 and 2) of a gage 21. This gage 21 is fixed to the upper end of a rod 22 which extends through a guide flange 230 of a vertically extending track or guide member 23 against the forward face of which the gage slides. The rod 22 extends downward through an opening 24 of a bracket 25 which is fixed centrally to a top cross member 26 of a yoke 27 made fast at opposite ends by inturned flanges 28 to the top of the slide 2. Slight variations in the thickness of the sole are provided for by a spring 30 surrounding the rod 22 and bearing in its lower end against the top face of the bracket 25 and at its upper end against a pin 31 extending transversely of the rod 22. This vertical movement is for the purpose of correctly positioning a counter-engaging gage or centering plate 35, which is also carried by the rod 22 against the upper face of the gage 21. The gage 35 has a sloping inner face 36 which engages beneath the rear end of the counter to properly position it relative to the sole in a lengthwise direction so that when the jack 1 is pushed rearwardly and the slide 2 raised upwardly, the parts are guided automatically into proper relative position. The nailing mechanism is then actuated to drive the nails in the block 10 through the sole-engaging

flange of the counter in the usual manner to make it fast on the upper face of the shoe sole.

It is sometimes desirable to move the gages 21 and 35 out of cooperative position with the jack and nailing block, as when shoes to which wood heels are to be applied, are being operated upon. For this purpose the guide member 23 is fixed to the outer end of a screw 40 which is slidable through perforations in a pair of spaced jaws 41 standing from a bracket 42 which is made fast to a fixed part of the machine frame 43. Threaded on the screw 40 between the jaws 41 is a knurled nut 44, by turning which the guide member 23 may be moved forwardly or backwardly relative to the machine frame and into and out of cooperative relation with the jack and nailing block. In order to permit this motion without binding, the perforation 24 of the bracket 25 through which the rod 22 passes is formed flaring outwardly toward both ends from an intermediate position to permit ready rocking of the rod 22 with reference to the bracket. The position of these parts when the gages are out of operative position is shown in dotted lines in Figure 3 in which also a modified construction of jack block particularly intended for use with wood heels is shown at 50.

As is well known the outer edge of the heel portion of the shoe to which a wood heel is to be attached is beveled off, and before the shoe is turned the upper is unattached to the heel portion of the sole. When a wood heel is to be affixed therefore, the block 50 has a marginal upwardly extending flange portion 51, as shown in Figures 3 and 4, within which the sole extends and against the top of which the edge of the counter may rest. The block 50 may be of a width sufficient to substantially fit the width of the sole if desired, as shown in full lines in Figure 4, but in order that a single block may serve for several sizes of shoe and therefore require infrequent change of blocks for different sizes, they may be made somewhat narrower than the shoe to be operated upon as indicated in dotted lines at 52 (see Figure 4). When such a narrow block is employed it is an easy matter for the operator to center the sole laterally on the block by placing his fingers beneath the edge of the sole and in contact with the edge of the block, the upper, as before stated, being unattached at this point to the sole and offering no obstruction to this action. The sole and counter gages are not used at this time, and in order to position the jack correctly rearwardly beneath the nailing block with these gages out of position, an adjustable stop herein shown as comprising a cap screw 55 is threaded in a boss 56 projecting inwardly from the yoke member 26. This

cap screw may be adjusted and then fixed in position by a lock nut 57 thereon so that when the jack 1 is pushed inwardly to impinge on the head thereof, it is correctly positioned 5 for vertical movement into operative relation to the nailing block. While as before stated the last is removed prior to the attachment of the counter and before the shoe is turned, it is usually preferable to turn the 10 toe portion of the shoe before the counter is attached, this being shown in dotted lines in Figures 1 and 3. When this is done the toe portion may be supported, when the shoe is initially placed on the jack, by means of 15 the toe rest 3, and when the jack is moved upwardly and the sole is engaged between the heel block and the nailing block, the forepart of the shoe is raised upwardly off the toe rest by the engagement of sole and 20 counter between the blocks 5 and 10 substantially as shown. If the forepart of the shoe is not turned prior to the attaching of the counter, the toe rest is likely to interfere with the downwardly extending upper 25 of the shoe.

Having thus described certain embodiments of this invention it should be evident to those skilled in the art that many modifications and changes might be made therein without departing from its spirit or scope 30 as defined by the appended claims.

I claim:

1. In a nailing machine, a nailing mechanism, a jack post movable horizontally into and out of position beneath said nailing mechanism and vertically into cooperative relation therewith, and a centering gage movable vertically with said jack post and against which a shoe supported on said post is brought when said post is moved to position it beneath said nailing mechanism, to center the shoe laterally in relation to said nailing mechanism.
2. In a nailing machine, a nailing mecha-

nism, a jack post movable horizontally into 45 and out of position beneath said nailing mechanism and vertically into cooperative relation therewith, and a centering gage comprising a curved member shaped to engage the end portion of a shoe movable vertically with said jack post and against which a shoe supported on said post is brought when said post is moved to position it beneath said nailing mechanism, to center the shoe laterally in relation to said nailing 50 mechanism.

3. In a nailing machine, a nailing block, means for supporting a molded counter about said block, a jack post movable horizontally into and out of position beneath 60 said block, and vertically into cooperative relation therewith, a block supported rigidly on said jack post and on which the unturned heel portion of a shoe may rest, the shoe upper extending about said block, 65 and means acting automatically on the raising of said jack post to position the counter and sole correctly related preliminary to nailing them together.

4. In a nailing machine, a nailing block, 70 means for supporting a molded counter about said block, a jack post movable horizontally into and out of position beneath said nail block and vertically into and out of cooperating relation thereto, a block 75 rigidly carried by said jack post and shaped to support the unturned heel end of a shoe, a gage against which the heel end of the shoe engages when said jack post is moved beneath said nailing block and movable vertically therewith for laterally centering said shoe, and a gage fixed to said first mentioned gage, and engaging and centering the counter laterally when the jack post is in raised position.

In testimony whereof I have affixed my signature.

MILTON L. DODGE.
